QUICK RELEASE MEANS FOR INCREASING
THE GAP BETWEEN DISKS UPON ENTRY
OF UNCRUSHABLES

James A. Eldridge, St. James, Manitoba, Canada

Application September 9, 1943, Serial No. 501,734

11 Claims. (Cl. 241—32)

1

This application constitutes a continuation-in-part of my application Serial No. 327,508, filed on the 2nd day of April, 1940, and relates to improvements in feed crushers, an object of my invention being to provide a device of the character herewithin described, which has been designed to meet the many requirements of various classes of user, and is of simplified, rugged and economical construction, having certain unique inventive features hereinafter to be described.

A further object of my invention is to provide a device of the character herewithin described in which the rotating and endwise movable parts, are mounted coaxially with respect to a non-rotatable supporting shaft, a rotatable crushing plate and screw conveyor being included among the parts mounted upon said shaft, and being adjustably end-shiftable with the shaft to vary the space between the said rotating crushing plate, and an opposed stationary crushing plate.

A further object of my invention is to provide, in a crushing machine, simplified means for providing an adjustable, but normally rigid and unyielding spacial relationship between the two crushing plates so that the coarseness or fineness of grind in a given batch may be perfectly uniform for that batch.

A further object of my invention is to provide in a device of the character herewithin described a unique manually operable and simultaneously acting combination valve cut-off and crushing plate release mechanism.

A further object of my invention is to provide a device of the character herewithin described which embodies a valve cut-off and crushing plate release mechanism automatically operated by the entrance of an obstruction between the crushing plates together with the provision of a further automatically operated gate valve in the outlet leading from the crushing chamber.

A still further object of my invention is to provide a device of the character herewithin described which includes means for varying the quantity of material precipitated into the base of my hopper and conveyed therefrom into the crushing chamber.

With the above more important objects in view and such other minor objects as may appear as the specification proceeds, my invention consists essentially in the arrangement and construction of parts all as hereinafter more particularly described, reference being had to the accompanying drawings, in which—

2

Figure 1 is a side elevation of my feed crusher showing certain parts in section and with certain other parts broken away.

Figure 2 is a longitudinal fragmentary representation, predominantly in cross-section, and illustrating my coaxial, shaft-mounted structure.

Figure 3 is a front elevation showing the external appearance of my feed crusher from this angle.

10 Figure 4 is a perspective illustration of my valve cut-off and crushing plate release mechanism.

Figure 5 is a perspective detail illustrating my crushing plate spacing and setting dial lock.

15 Figure 6 is a detail in elevation showing the means by which I may vary micrometrically the opening of my gate valve.

Figure 7 is a detail in front elevation illustrating a modification of the arrangement of Figure 6.

20 Figure 8 is a side elevation showing means by which my valve cut-off and crushing plate release mechanism may be automatically actuated when foreign matter enters between the crushing plates.

Figure 9 is a side elevation of my feed crusher showing an alternative means by which my valve cut-off and crushing plate release mechanism may be automatically actuated when foreign matter enters between the crushing plates.

30 Figure 10 is a perspective detail illustrating a part of the mechanism employed in connection with Figure 9.

Figure 11 is a detail in elevation illustrating 35 the means by which my discharge outlet may be automatically closed and reset by the operation of my valve cut-off and crushing plate release mechanism.

Figure 12 is a detail illustrating the use of a 40 sleeve or collar in place of a spring between my setting dial and barrel cam.

Figure 13 is a detail illustrating the use of a transverse pin in place of a spring between my setting dial and barrel cam.

45 Figure 14 is an elevation of the structure of Figure 6 at right angles thereto.

In the drawings like characters of reference indicate corresponding parts in the different figures.

50 My feed crusher comprises the usual hopper A, conveyor screw B, crushing chamber C, crushing plates D and E, and driving pulley F, all suitably mounted upon a supporting structure G.

Briefly stated, the pulley F rotates about the 55 stationary but end-shiftable supporting shaft I,

the rotating crushing plate D being secured for rotation with the pulley via a crushing plate holder, in horizontal alignment with the stationary crushing plate E, while the conveyor screw B is bolted to the said plate holder as illustrated most clearly in the accompanying Figure 2, to rotate with the pulley and the plate D.

Means are provided in my invention for positively adjusting the space between the plates D and E and for rigidly and unyieldingly maintaining the space desired, excepting only when a hard and damaging obstacle comes between them, such means consisting of a setting dial 2, which rotates the screw-threaded stem 3 coaxially positioned within the internally threaded forward end of the supporting shaft 1.

Means are also provided for manually and simultaneously effecting the closing of a hopper valve 4 adjacent the base of my hopper A and permitting the separation of the plates D and E to their maximum extent in the event of a damaging obstruction finding its way between the crushing plates D and E, this mechanism being clearly illustrated in the accompanying Figures 1 and 3, from which it will be seen that upon the front wall 5 of the base casting 6 of my hopper is a stationary cylindrical cam thrust receiving element 7 provided with an external spiral cam track. Engageable with this member is a swivelling barrel cam 8, held against the track of the cam 7 by means of the spring 9 which spring, it should be particularly noted is of considerable stiffness such as will not yield to mere increases in the volume of material tending to enter between the plates, for which reason it will clearly be recognized that when the plates are set a given distance apart, no variation in the volume of material entering between them is possible, and consequently a uniform fineness of grind is obtainable for any given setting.

In this context I would therefore explain that the resistance of the spring 9 should be so adjusted for operation of the crusher with engines of various H. P. ratings such that it will yield only under stresses imposed by pressure above that which the material to be ground exerts at a given H. P. rating. For example by rotating handwheel 2 to left or right on stem 3 and so adjusting the distance between it and the cam 8 I may set the spring 9 at a resistance of about 500 lbs. when used with an engine of from 35 to 40 H. P. and at this setting, such mere increases of pressure between the plates as might be effected by masses of wet grain, or different or harder grain, will not be sufficient to separate the plates.

The foregoing constitutes a significant difference over conventional crushers, wherein one plate is positioned in yielding relationship to the other, the pressure at which excessive yielding takes place, being experimentally determined by the user after he has started the machine in operation and commenced to grind. If for instance he finds that the material being discharged is too coarse, he exerts more pressure on the spring which in turn increases pressure on one of the plates. Obviously under such conditions, when the character of the material changes, as from wet to dry or vice versa, the quality of the grind will differ.

Secured to the barrel cam and extending upwardly therefrom is a cam lever 9' normally held in a recess 10, in a shaped casting 11.

Extending substantially parallel to the upper portion of the lever 9', is the hopper valve lever 12, upon which are a series of projections constituting a ratcheted rack capable of being engaged by a projection in the form of a pawl 13 upon the lever 9'. The lever 12 is angulated and suitably secured at its lower end to the hopper valve 4 already referred to and obviously upon kicking the lever 9' out of its catch or recess 10, the same will rotate to the right under the swivelling action of the cam 8, the pawl 13 will leave the associated rack whereupon the lever 12 will move upwardly under the influence of the spring 14, thereby closing the valve 4.

Having now described my invention in its essentials, I will proceed to describe the same in detail.

My supporting structure G comprises a bed-plate 15, to one end of which is bolted an up-standing leg 16 upon the apex of which is my main bearing 17, in which the supporting shaft 1 is mounted. Upon the forward end of the bed-plate is an upstanding wall 18 provided with an enlarged aperture 19 through which the conveyor screw B and the shaft 1 extend, the housing 19 which together with the wall 18 forms my crushing chamber C, being suitably secured at the rear side of the wall 18, while on the forward side thereof is positioned the base casting 6 already referred to, the hopper A, being suitably positioned upon the apex of the base casting.

At this point I would mention that I may if desired, provide a trap 20 below the base casting, the same being detachable and suitably clipped thereto as most clearly illustrated in the accompanying Figures 1 and 3 in which case no base will be provided to the base casting 6, the purpose of this trap being to permit surplus material or foreign matter to accumulate therein, from which it may periodically be conveniently removed.

I should also mention at this point that an outlet 21 positioned at the angle illustrated in the accompanying Figure 3, is formed integral with the housing 19 of my crushing chamber, to which if desired, a conduit may be attached, through which material crushed is blown under the influence of the fan blades, which are attached to the rotating crushing plate later to be described in detail.

The supporting shaft 1 is mounted in the element 7, which as has been previously mentioned, is set within the front wall 5 of the base casting 6, this member being clearly illustrated in cross-section in the accompanying Figure 2, from which it will be seen that my shaft is prevented from rotation by the provision of the key 22 but is free to slide endwise under the conditions to be hereinafter described. From the accompanying Figure 1, it will be seen that the external surface of the element 7, takes the form of a frusto-conical wall 23, around which is formed a spiral cam track 24.

It will be seen that the forward end of my supporting shaft 1 lies in the aperture 25 which extends through the casting 7 and that the same is internally drilled and tapped a short distance to receive the externally threaded end of the stem 3 already referred to. A collar 26 integral with the stem 3 is normally held against the shoulder 27. Keyways 28 and 29 in the shaft 1 and the element 7 respectively, receive the key 22 and prevent rotation of the shaft while permitting longitudinal movement thereof.

The stem 3 extends forwardly and terminates in the crushing plate spacing and setting dial 2 already referred to, the setting dial being screwed the desired distance for any particular spring setting as already described, onto the projecting end of the stem 3 and prevented from independent movement by means of the split pin 30 which extends transversely through the boss of the dial and the stem. In this way the distance between handwheel 2 and collar 26 is rigidly fixed after which rotation of the handwheel will necessarily involve rotation of stem 3 in a fixed plane thus acting to end-shift shaft 1. A sleeve 31 internally screw-threaded if desired may be placed upon the stem 3 to the rear of the dial 2 solely for centering the spring 9.

My pulley F which is journalled upon the supporting shaft 1, runs on ball-bearing assemblies 32 and 33 and by reference to the accompanying Figures 1 and 12 it will be seen that the inner ball races of these assemblies are held against a tendency to move to right or left along the supporting shaft 1, by means of the diametrically split thrust bearing rings 34 which set inside into annular recesses 35 in the shaft provided for that purpose. The bearing rings 34 are held within the recesses 35 by means of the said inner ball races which it will be clearly seen extend around and act as collars for the recessed parts of the rings 34, while the upstanding portions thereof act as annular buttresses to prevent left or right hand endwise movement. The assembly 32 is suitably housed about by a casing 36 which is secured to the pulley F while assembly 33 is enclosed by housing 19.

In order to provide satisfactory lubrication for the assemblies 32 and 33, I have provided three outwardly projecting interceptors or paddles 37, the same being secured to the shaft 1, from which it will be apparent that when a quantity of oil is admitted to the hollow center or bath 38 within the pulley through the oil hole 39, the rotation of the pulley will cause a swirling action in the oil body, which coming in contact with the interceptors will cause considerable agitation and splash, thereby providing particularly satisfactory lubrication.

Attached to the forward end of the pulley F is my rotatable crushing plate holder 40, which will not be described in detail except in respect to one unique feature as a crushing plate holder necessarily forms an integral part of all crushing machines. This feature resides in the provision of slots 42, by means of which the fan blades 43 are adjustably held within the crushing chamber C so that the effective width thereof may be varied to produce an adjustable air blast and it will be obvious from the illustration of this detail in the accompanying Figure 1 that these fan blades are secured to the holder 40 by means of stud-bolts and nuts, adjustment being made after the removal of the housing 19.

My conveyor screw B is provided with the flange 44 at the rear end thereof through which bolts 45 extend and whereby the conveyor screw is secured to the boss 46 of the crushing plate holder 40, so that the two will rotate as a unit, the sleeve 47 of the conveyor screw being spaced from the shaft to avoid friction as clearly illustrated in Figure 2.

The swivelling cam 8 which is designed to move in a spiral direction against the thrust element 7, is of the barrel type and I may provide thereupon either one continuous circumscribing spiral cam track 48 or alternatively two or three such tracks as in the preferred embodiment illustrated in the

accompanying Figure 1, wherein I have designated the two visible peaks Y and Z, peak X being out of sight at the rear so that this member may be considered as a modification of the well-known crown ratchet except that it is not in this instance, employed in association with a complete ratcheting motion or with any associated pawl, but on the contrary, is designed to swivel back and forth against the cam track 24 of which naturally there will be a corresponding number of corresponding gradients, but it will not override the track 24 as a crown ratchet would in its conventional operation.

Secured to an outstanding projection 49 upon the wall of the cam 8, is the angulated and upwardly extending cam lever 9' already referred to, the same extending through the catch 10 of the casting or plate 11, which is of the configuration clearly illustrated in the accompanying Figure 4. To the right hand side of the catch 10 is a lead-in track 50 (which may also function as a cam track as described hereinafter) to facilitate the manual operation of moving the lever into the catch, this lever being preferably formed of spring steel for this purpose.

To the left of and slightly below the catch or recess 10, is a rectangular slot 51 through which my valve lever 12 extends, the same being angulated to the configuration clearly illustrated in the accompanying Figures 1 and 4, and from these figures also it will be noted that a ratcheted rack 52 is positioned along one side of this lever with the ratchet teeth projecting slightly and capable of being engaged by the pawl 13 upon the cam lever 9'. The spring 14 already referred to, is secured at its upper end preferably by means of the bolts which hold the casting 11 in position while the lower end is suitably secured to the valve lever at a point below the rack 52 and during the operation of the machine or at times when the ratchets are engaged by the pawl, this spring will be in tension.

A link 53 is freely secured at the end of the angulated portion 54 of the valve lever, this link extending through an aperture at the top left hand corner of the side wall 55 of the base casting 6, and thereacross. To this member is secured a gate valve 56 designed to move under the influence of the link 53 and the associated lever 50 through an arc to admit or cut-off the flow of material to be crushed between the conical portion of the hopper A and the base casting 6, in which the conveyor is located.

In operation, it will be perceived that the rotating and stationary plates D and E having been set or spaced the desired distance apart in the manner to be presently described, it is possible in an emergency to bring about separation of the rotating plate from the stationary plate to a predetermined maximum distance and simultaneously to close the gate valve 56 in the event of a damaging obstruction finding its way between the crushing plates D and E. This is accomplished by the operator kicking or throwing the cam lever 9' upwardly so that it disengages the catch 10, whereupon it will swing to the right together with the swivelling cam 8 and as it swings of course, the cam will travel to the left with respect to the accompanying Figure 1, against the cam track 24.

The entire supporting shaft and the continuation thereof in the form of the screw-threaded stem 3, is now free to move to the left together with the conveyor screw B, the driving pulley F and of course, the attached crushing plate holder 40 and rotating crushing plate D. The crusher can

then be stopped of course, the obstruction removed from the crushing chamber through the outlet 21 if possible, after which it may be restarted and the cam lever swung to the left until it comes to the lip 50 over which it rides into the catch 10, the spring 9 being moved longitudinally to the right under the influence of the above action and carrying with it the supporting shaft, screw-threaded stem and the remaining mechanism already mentioned back to the original setting.

In this context it is of importance to recognize a unique characteristic of the present invention and which consists in the fact that my crushing plates are only forced apart by foreign matter of sufficient hardness to constitute what I refer to herein as a "damaging obstruction" but as soon as the existence of a damaging obstruction between the plates is recognized by the operator, he unlocks the lever 9 in the manner I have clearly explained, which releases the plates, the shaft, and all associated parts from all spring pressure. There is no increase of pressure on any spring associated with my device upon the separation of the crushing plates. By contrast, all spring pressure as applied to the crushing plate D is released when the lever 9 is unlocked, the plate D separating itself from the plate E to the maximum extent or in other words, moving leftwardly with shaft 1 until the casing 36 comes into contact with the bearing 17, predominantly because of the interposition of the damaging obstruction. At such time the spring 9 (if a spring is used) is completely relaxed.

In the automatic embodiment of my crusher, it will clearly be recognized that the release of all spring pressure following the momentary increase of pressure consequent upon the introduction of a damaging obstruction between the plates is self-initiating as is explained fully elsewhere in this description.

It should similarly be noted that although I provide a spring 9, I might instead substitute a collar 56 (Figure 13) of similar length to the spring shown in Figure 1, or again I might provide a pin 57 (Figure 14) which would extend transversely through the stem 3 against the exterior face of the cam 8 when in the position shown in Figure 1. Such modifications are suggested mainly to indicate that a spring 9 is not absolutely essential, although for practical reasons preferable, since it will be recognized that if a collar or a pin were employed, I could still effect a longitudinal and leftwise release of my shaft and crushing plate D if the lever 9 were released from the catch 10. In such case, the damaging obstruction would force the plate D apart which in turn would carry with it the shaft 1, the stem 3 and the said collar or pin, these latter members causing the cam to swivel as soon as the lever 9 is released from the catch, precisely as takes place by the use of the spring 9.

In this connection it is appropriate to emphasize the fact that my lever 9 is of slightly resilient character in fact, and so, if I elected to substitute a collar or pin, the necessary initial yielding or separation of the plates upon the introduction of a damaging obstruction, would still take place, since the plate D would then pull upon the barrel cam via the shaft 1 and the stem causing said cam to swivel slightly against the associated stationary element, such limited swiveling action being permitted owing to the resiliency of the lever.

In the emergency releasing action of the cam 75 lever 12 the shaft 61 being provided with a stop

lever 9, it will be obvious that the attached pawl 13 must leave the ratchet teeth on the rack 52 whereupon the valve lever must lift endwise and upwardly under the influence of the tension spring 14 to close the hopper valve 56 as already described and in the resetting action, after the cam lever has been reset, the valve lever is simply pushed down while the pawl rides against the ratchet until the associated gate valve is opened to the desired extent.

As has already been stated, my setting dial 2 is secured to rotate the stem 3. When so rotated, it is obvious that the externally screw-threaded end of the stem will move the supporting shaft 1 to the left or right, reference being made to the accompanying Figure 2 in this connection. This has the effect of moving the conveyor B also and in addition, the rotating crushing plate D so that it is possible with this machine to regulate the fineness of any particular grind. To lock the setting dial, reference is made to the Figures 3 and 5 of the accompanying drawings, from which it will be seen that the same is provided around its perimeter with a number of recesses, into which the bolt 51 may be received, this bolt being secured in the wall 5 of the base casting 6 and preferably formed of spring steel which will permit the dial 2 to be rotated while the bolt remains in light engagement. When the desired setting is reached, the lock 53 which is simply formed of a piece of a crank shaped rod terminating in a ring designed to extend around the collar 31 behind the dial, is slipped over the bolt to lock the dial against further movement. (The ring forming part of this detail being also shown in Figure 1).

Any arbitrary nomenclature may be resorted to upon the dial 2, the most logical being a graduation of one-sixteenth of an inch, such graduation representing the spacing between the plates D and E.

It should be pointed out that it is desirable to provide means for varying the aperture between the hopper valve 56 and the front wall 5 to govern the flow of material into the crushing chamber and in the accompanying Figures 1 and 6, I illustrate two methods by which this may be accomplished, the method illustrated in Figure 1 being considerably less accurate than that illustrated in Figure 6.

The former method comprises the provision of a line-up of apertures 59 formed in the length of the valve lever 12, a key 60 in the form of a piece of round rod being insertable through any of the apertures 59 above the upper surface of the casting 11, the provision of this member being for the purpose of acting as a stop to limit the downward movement of the lever 12 in the resetting operation and hence, the opening of the gate 56.

In the embodiment illustrated in Figure 6, my ratcheted rack 52 and the pawl 13 are dispensed with and instead of these members, I provide a screw-threaded shaft 61 provided at its upper end with a knurled thumb screw 62, the shaft extending through the angulated portion of the valve lever 12 and through an internally screw-threaded slot 63 secured to the lever in the location illustrated. The slot 61 formed in the casting 11 and through which the valve lever 12 extends, will in this case, be increased in area to permit the inclusion of the shaft 61, which at the lower end thereof extends through an off-set lug 64 projecting from a sleeve 65 freely slideable upon the valve lever 12 the shaft 61 being provided with a stop

collar 66, and at the extreme lower end thereof with a retaining nut 66' through which a split lock pin extends, so that the shaft 61 is free to rotate in the lug 64 without moving endwise therein.

Upon the cam lever 9' is an offset block 67, the lower surface of which is designed to engage with the perimeter of the sleeve 65 and from the foregoing arrangement it will be apparent that when my valve cut-off and crushing plate release mechanism is in the "set" position, rotation of the thumb screw 62 will have the effect of shifting the valve lever 12 endwise upwardly or downwardly, thereby varying to any exact extent desired, the gate 56 and consequently, the aperture leading from the hopper to the crushing chamber.

In the foregoing arrangement as illustrated in Figure 6, it will be apparent that in the resetting operation, it is necessary first to depress the valve lever 12 so that the sleeve 65 is below the level of the block 67 before throwing the cam lever 9' to the left and into its retaining catch and before releasing the said valve lever but obviously by the provision of a block 67' having the bevelled surface illustrated in Figure 7, it is possible to throw over the cam lever 9' into its catch before depressing the valve lever 12 since the sleeve may now ride downwardly against 67' without interception thereby, space being provided in this instance for the necessary sideways movement of the valve lever, although a moment's consideration of Figure 7 will reveal that flexure either of shaft 9' or 12 or both would allow sleeve 65 to ride downwardly upon application of a downward effort on the upper end of shaft 12, via the bevelled surface of block 67' and engage with the under-edge thereof even if no allowance for sideways movement were permitted by slot 51.

From all the foregoing, it will be recognized that I have produced a crusher wherein separating movement of the rotating plate from the stationary plate may be effected, to all intents and purposes instantaneously and without any muscular effort whatever worth speaking of such as would be necessary for instance in throwing a lever to separate a plate against resistance of a spring. The "snap action" employed for the separation of my crusher is a much more pleasing and mechanically satisfactory action than is the action of manually pulling, pushing or rotating a lever or wheel for instance, through a given distance and which takes appreciable time to accomplish in any event. Under such conditions as the existence of a damaging obstruction between a pair of crushing plates, the operator naturally desires above all things to be able to act expeditiously and feel that he is doing so, and this is possible in a most gratifying way in the case of the present invention, the plates of which a child can operate every bit as satisfactorily as an adult immediately the harsh noise of a damaging obstruction between the plates is heard. In such case it will be recognized that the lever 9' can equally well be kicked out of the catch with the knee or the foot if for instance when the operator's hands are full.

To conclude this description of the main structure, I desire to explain that the pitch angle of either the spiral surfaces 24 or 48 or preferably both, should be greater than the angle of static friction which supervenes at the minimum H. P. likely to be employed. With an engine of 35-40 H. P. the minimum pitch angle should be approximately 14° from the plane of rotation when made out of cast iron. In this context however I wish it to be particularly understood that I do not con-

sider myself bound by the above stated pitch angle, since it is to be noted that with a lesser pitch angle my lever 9' could still be manually thrown to the right after release from catch 10, and in the latter case by its inherent resiliency and tendency to spring in the direction indicated by arrow 68 (Figure 1) after being forced out of the said catch, and which resiliency would cause it to press against and so ride clockwise (when viewed from the right hand end of the crusher) against the curved lip 50 (Figure 4), especially if made somewhat steeper than shown and lubricated.

In the accompanying Figure 8, I have provided means whereby my valve cut-off and crushing plate release mechanism may be caused to operate automatically upon the accidental introduction of a hard piece of foreign matter between the crushing plates, the same comprising an offset arm 69, which may be positioned at any convenient point upon the collar 31 either directly or freely upon a ring as illustrated, a horizontal push-rod 70 being secured in this member for end-shiftable movement in the direction of the arrow to operate a small pivoted plate 70' of the configuration clearly illustrated, this plate being designed to move in the arc shown by the adjacent arrow about the stud 71 which is secured in an outwardly projecting plate 72 secured to the wall 5 and it will be understood that the rear end of the rod 70 pushes against the vertical face of the plate 70' to actuate the same in the direction of the adjacent arrow.

When so actuated, the link 13 will travel downwardly as it is to be understood that the lower end of this member is secured to the plate 70' at the point illustrated, there being a substantially similar plate 74 at the upper end of the link 13 and pivotally mounted in or beneath the casting 11 and just in front of the catch 10 in which the cam lever 9' resides in the "set" position. If desired, the auxiliary trigger 74' may be added as this is a somewhat more convenient means for operating the whole associated mechanism than the cam lever 9'.

It is to be understood that the plate 74 is designed to travel in the direction of the adjacent arrow when the link 13 is drawn downwardly and when this occurs, the corner 75 of the plate 50 74 bears against the lever 9' to disengage the same from its catch, whereupon it swings to the right in the manner already described in detail, to release the adjacent valve lever 12 and throw the rotatable crushing plate away from the stationary crushing plate by the full predetermined distance and it is to be understood that the foregoing movement takes place when a hard piece of foreign matter enters between the grinding surfaces of the crushing plates, thereby forcing them apart to a slight extent, which forcing action is felt by the stem 3 and naturally the associated collar 31, and hence the offset arm 69 all of which move to the left with respect to the accompanying Figure 8.

Finally in connection with this detail, I would explain that the push rod 70 is freely held medially of its length by means of the tie block 75' which is provided with a horizontal aperture therefor and a square vertical aperture for the cam lever 9', the arrangement being that the rod is free to end-shift through its aperture in the tie block but is swung around with the cam lever taking the arm 68 with it when the release mechanism illustrated in the accompanying Figure 5 70 is tripped as explained. Following the leftward

"kick" by rod 70 which actuates plate 70' as aforesaid, the resulting rotation of lever 9' carries parts 69, to 70 and 75' around with it, so that the rod 70 becomes disengaged from plate 70', which latter rotates in a fixed vertical plane as already explained, being secured to the hopper base.

In the accompanying Figures 9 and 10 I have illustrated an alternative means whereby my hopper valve cut-off and crushing plate release mechanism may be caused to operate automatically upon the accidental introduction of a hard piece of foreign matter between the crushing plates, the same being in certain respects preferable to the embodiment of Figure 8, as more positive, has neater appearance and less liable to damage in the wear and tear of the heavy use to which machines of this character are placed.

This embodiment calls for the use of a block 82 extending from which is a trigger similar to the trigger 74' and to which accordingly I have assigned this numeral in the accompanying Figures 9 and 10, the block itself, however, being of somewhat altered form as compared with the block 74 and functioning as a lever of the first class to actuate the cam lever 9'.

It will be seen that the block 82 is pivotally mounted as at 83 in the casting and is provided with an upwardly projecting abutment 84 while freely attached to the lower corner 85 is a rod 86 extending diagonally through the hopper A and terminating in the bell-crank-action plate 87, which is pivoted in the bearing plates 88 projecting upwardly from the main bearing 17.

The nose 89 of the plate 87 terminates in a screw-threaded collar 90, through which extends a set screw 91, the end of which bears against the shaft 1 and from the foregoing description it will be apparent that upon forcible separation of the crushing plates due to a damaging obstruction, the shaft 1 will move to the left with respect to the accompanying Figure 9 for reasons already adequately described and in doing so, will cause the plate 87 to rotate about its pivot point in a clockwise direction as indicated by the arrow 92, thus shifting the rod 86 in the direction of the arrow 93, which in turn will rotate the block 82 about the pivot point 83 counterclockwise in the direction of the arrow 94.

This action obviously will compel the abutment 84 to force the cam lever 9' out of its recess 10, whereupon the same will swing with the barrel cam 8 in the manner already adequately described and of course, at the same time, the valve lever 12 will be released and the gate 56 to prevent further material from gravitating downwardly into the base of my hopper.

In the accompanying Figure 11 I have illustrated a simplified method whereby the discharge of material from the crushing chamber through the outlet 21 may be shut off in the event of the crushing plates being accidentally separated through the introduction of a piece of foreign matter therebetween, with the consequent inability of the crushing plates to continue a thorough grinding action. In this connection it will be understood that when a particularly fine grind is required, even a small quantity of imperfectly ground material discharged into the mass of ground material, would necessitate the sifting of the whole with consequent expense and loss of time involved. For this reason, it is necessary to provide means whereby any material remaining in the crushing chamber at any time that the plates are forcibly separated as above

mentioned, shall be prevented from being conveyed by the fanning action within the chamber upwardly into the ground mass.

From the accompanying Figure 11 therefore it will be seen that I provide a gate valve 76 which is hinged at the location illustrated and is designed to cover the passageway through which the ground material travels, this valve being provided at the point at which it is hinged with an elongated rod 77, angulated downwards at the end 78 and it is to be understood that the downward angulation is in the vertical plane of the outstanding projection 49 to which the cam lever 9' is secured, so that the rod 77 actually is of substantial length as it has to extend from the outlet 21, which is in the plane of the crushing chamber 19, to the member 49, for which reason an intermediate supporting bracket 79 is provided, the same being mounted upon the side wall 80 of the hopper base.

To provide for actuation of the rod 77 and the gate valve 76, I provide a trip 81 which extends outwardly from the root of the cam lever 9', the same being provided with a domed end which engages with the downturned portion 78 and from this arrangement, it is obvious that when the cam lever 9' travels in the direction of the adjacent arrow as already described in detail, the trip 81 will rise and obviously, will permit the gate valve 76 to drop.

Obviously, the gate valve 76 will not drop to the closed position instantaneously in view of the blast of air impinging thereagainst. It will drop, however, to an extent sufficient to deflect the remaining partially crushed contents of the crushing chamber outwardly and downwardly through the aperture 82 so that the same will not mix with the thoroughly ground mass and it will be understood of course, that I use the word "remaining" advisedly because in the meantime the valve 56 has closed as already described so that there is only a limited quantity of material to be discharged from the crushing chamber.

Finally it should be noted that a stop 83 which may be in the form of a transverse projecting strip, extends across the floor of the outlet 21 against which door 76 is intended to rest at an incline when closed, this stop also assisting to prevent the return of small amounts of material discharged after the crushing plates have been separated.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this invention may be made within the scope of the accompanying claims without departing from the spirit and scope of the same it is intended that all matter contained in the accompanying specification shall be interpreted as illustrative only and not in a limiting sense and I desire only such limitations placed thereon as justice dictates.

What I claim as my invention is:

1. A material crusher comprising in combination, a supporting structure, a hopper, a crushing chamber, crushing plates therewithin, a non-rotatable, end-shiftable shaft, a driving mechanism for actuating at least one of said crushing plates, the plate actuated thereby being held

against independent linear movement on said shaft and acting to end-shift the same when separated from the other plate by a damaging obstruction, said driving mechanism also being mounted for rotation upon said shaft, crushing plate separating mechanism comprising in combination, a stationary cam thrust receiving element provided with a spiral face, a swivelling thrust cam designed under normal conditions releasably to hold said shaft against end-shifting and the plate thereon against separation from the opposing plate, said cam and said element being mounted co-axially with respect to said shaft, releasable means for holding a predetermined area of said swivelling cam in bearing contact with said stationary element in the operable position of said crushing plates, the release of said means allowing said swivelling cam to move in a spiral direction against the face of said element to permit end-shifting of said shaft and separation of said plates.

2. A material crusher comprising in combination, a supporting structure, a hopper, a crushing chamber, a pair of crushing plates therein, an end-shiftable shaft, one of said crushing plates being mounted for rotation on said shaft but being held against independent linear movement thereon so as to end-shift said shaft when a damaging obstruction enters between the plates, separating the same; automatic crushing plate quick releasing mechanism actuatable upon the introduction of a damaging obstruction between said plates and upon the consequent separation thereof, including a swivelling thrust cam, designed to maintain said crushing plates in releasable spaced relation, a lever projecting from said cam, a lock for said lever and means operable upon the initial end-shifting of said shaft to unlock said lever and permit rotation of said cam to allow the further end-shifting of said shaft to a predetermined maximum extent and the separation of the plate thereon from the other plate also to a predetermined maximum extent.

3. A material crusher comprising in combination, a supporting structure, a hopper, a crushing chamber, a pair of crushing plates therein, a supporting shaft, automatic crushing plate quick releasing mechanism actuatable upon the introduction of a damaging obstruction between said plates and upon the consequent separation thereof, including a swivelling thrust cam, designed to maintain said crushing plates in releasable spaced relation, a lever thereon, a lock for said lever, means for unlocking said lever operable upon the initial separating movement of one of said plates from the other under the influence of an obstruction entering therebetween, the unlocking of said lever by said means permitting the rotation of said cam and thereby allowing the further separation of said plates to a predetermined maximum extent.

4. A material crusher comprising in combination, a supporting structure, a hopper, a crushing chamber, a pair of crushing plates therein, a non-rotatable shaft, at least one of said plates being mounted for rotation on said shaft; a crushing plate releasing mechanism, comprising in combination with the foregoing, a stationary cam thrust receiving element, a swivelling barrel-type thrust cam having a spiral cam face, releasable means for holding a predetermined area of said cam face in bearing contact with said cam thrust receiving element in the operable position of said crushing plate, the release

of said means allowing said swivelling cam to move in a spiral direction against the face of said element to permit the separation of said plates.

5. In a material crusher and in association with a crushing plate releasing means, a cam lever secured thereto, a lock for said lever, a hopper valve, a hopper valve closing mechanism in association with said lever, said hopper valve closing mechanism comprising a valve lever, a projection on said valve lever and a projection on said first mentioned lever, said projections being in mutually intercepting contact in the open position of said hopper valve but out of contact when closed and spring means operably connected to said valve lever to compel actuation thereof and the consequent closing of said hopper valve upon the unlocking and consequent release of said first mentioned lever.
20. 6. In a material crusher a non-rotatable end-shiftable shaft, a pair of opposed crushing plates, one of said plates being co-axial with said shaft, one of said plates being also shiftable with and by said shaft, said shaft being provided with an internally screw-threaded drilling in one end thereof, a rotatable, externally screw-threaded stem extending into said drilling adjustably to end-shift said shaft and thereby adjust the proximity of one of said crushing plates with respect to the opposing one, and means for holding said stem against linear movement during the operation of adjustably end-shifting said shaft as aforesaid.
35. 7. In a material crusher, a non-rotatable, end-shiftable shaft, a pair of opposed crushing plates, means for driving one of said plates, one of said plates being shiftable with and by said shaft, a swivelling thrust cam mounted co-axially with respect to said shaft, a stationary cam thrust receiving element, locking means for holding said cam in engagement with said element at least in the operative position of said shaft, an internally threaded drilling in the end of said shaft, an externally screw-threaded stem engageable with the thread in said drilling, said stem being rotatable to end-shift said shaft and thereby adjust the proximity of one of said crushing plates with respect to the opposing one, means for holding said stem against linear movement during the operation of adjustably end-shifting said shaft as aforesaid and means for unlocking said cam locking means to permit rotation thereof and consequent independent end-shifting of said shaft and the spacing of the plate shiftable therewith and thereby as aforesaid from said opposing plate when a damaging obstruction enters therebetween.
50. 8. A material crusher comprising in combination, a supporting structure, a hopper, a crushing chamber, a pair of crushing plates within said chamber of which at least one is rotatable, means for driving at least one of said plates, an end-shiftable, non-rotatable supporting shaft, means for permitting movement of one of said crushing plates with said shaft to vary the distance between the same and the other crushing plate, a screw-threaded extension on the end of said shaft engageable with a screw-threaded portion at one end of said shaft and means for rotating said extension to end-shift said shaft via said threads and move the said one plate therewith, all while said machine is in operation.
65. 9. In association with the device as defined in claim 6, a setting dial upon one end of said screw-threaded stem, a locking device for holding said
70. 75.

setting dial against rotation, said locking device comprising in combination with a plurality of spaced recesses upon the perimeter of said dial, a sprung bolt in light bearing engagement with said perimeter and means designed to engage said bolt and hold the same in engagement with any desired one of said recesses.

10. In association with the device as defined in claim 8, a setting dial upon one end of said screw-threaded stem, a locking device for holding said setting dial against rotation, said locking device comprising in combination with a plurality of spaced recesses upon the perimeter of said dial, a sprung bolt in light bearing engagement with said perimeter and means designed to engage said bolt and hold the same in engagement with any desired one of said recesses.

11. In a material crusher having an end-shiftable supporting shaft and a crushing plate mounted thereon for movement along its axis of rotation therewith, means including a lever actuatable while said crusher is running and lock therefor for securing said shaft against end-shifting and said plate against yielding during normal operation with respect to an opposing plate, said means also including at least one cam element and a cam contacting element, said lever being secured to one of said elements, said cam element being inclined in excess of the angle of static friction to facilitate movement of said

lever following its release from said lock without the application of further effort, and consequent separation of said shaft mounted plate from said opposing plate a predetermined maximum distance.
